UNITED STATES PATENT OFFICE.

ELMER I. YOUNG, OF NEW YORK, N. Y., ASSIGNOR TO POLAR STAR COMPANY, A CORPORATION OF PENNSYLVANIA.

ICE-CREAM FREEZER.

949,692.

Specification of Letters Patent. Patented Feb. 15, 1910.

Application filed February 10, 1908. Serial No. 415,157.

To all whom it may concern:

Be it known that I, ELMER I. YOUNG, of New York city, New York, have invented a new and useful Improvement in Ice-Cream Freezers, which invention is fully set forth in the following specification.

This invention relates to improvements in ice-cream freezers, the general objects being to provide a freezer, especially adapted to 10 household use, which shall be of simple, durable and cheap construction, easily operable, and the parts of which may be readily assembled and disassembled.

The novel points in construction and combination of elements constituting the present invention, and which contribute to the attainment of those objects, may be more readily explained and understood by reference 15 to the accompanying drawings, wherein I have shown what is now believed to be the preferred embodiment of the invention, and wherein—

Figure 1 is a perspective view of the freezer with portions of the walls of the ice-receptacle and cream-can broken away to 20 more clearly show the parts within; Fig. 2 is a detail perspective view illustrating the connections between some of the elements; Fig. 3 is a vertical sectional view of the 25 freezer, the line of section extending through the axis of the cream-can; and Fig. 4 is a horizontal section on line 4—4, Fig. 3.

5 is an ice-receptacle preferably in the form of a bucket of cylindrical shape. It 30 may be constructed of wood, compressed fibrous composition such as commonly used in making buckets and other receptacles, but (especially for freezers of small size) I prefer to use metal, such as galvanized iron 35 or tin. As illustrated in the drawings, the edge of the upper open end of the ice-receptacle is strengthened by bending the sheet metal around wire 6.

7 is an opening in the side of the receptacle for the overflow of salt-water, the edge 40 of this opening being strengthened by a wire in a manner similar to that above explained.

8 is a cross-bar extending across the open 45 end of the ice-receptacle; it may take any suitable form, such as a casting, but, as illustrated in the drawing, is preferably made of a piece of heavy sheet metal stiffened and strengthened along its edges by bending said

edges over a wire 9. At one end of the 55 cross-bar the projecting ends 10—10 of wire 9 are bent downward through openings 11—11, respectively, in the wall of the ice-receptacle, and then upward into contact with the under-side of the cross-bar, thus 60 forming a hinge attaching one end of said bar to the ice-receptacle. At the other end of the cross-bar the wire 9 is looped and bent to form a handle or grip 12 and projections 13—13, the latter adapted to spring 65 over and grip under the rib around the edge of the receptacle, thereby holding the detachable end of the cross-bar in engagement with the ice-receptacle while the freezer is being operated. The handle or grip 12 of 70 the wire stands out clear of the outer surface of the ice-receptacle so as to be easily grasped in disengaging the parts of the freezer. About mid-way of its length the cross-bar has therethrough a squared opening 15 surrounded by an up-turned flange 75 16, the purpose of which will be hereafter explained.

17, which will be hereinafter designated the cream-can, is a receptacle for the cream 80 or other mixture to be frozen. As shown in the drawing, it is of cylindrical form and is provided with a cover 18 for closing its upper open end, the lower edge of said cover being adapted to bear against an outwardly 85 projecting rib 19 around the can near its open end.

21 is an elongated flange or tube extending upward from the top of cover 18 about a central opening therethrough, this flange 90 preventing salt-water or other foreign material from finding its way down through the top of the can into the cream-receptacle.

22 is a stub-axle passing through the bottom of the can at about the center thereof 95 and soldered or otherwise rigidly secured in place; this stub-axle also passes through and is soldered or otherwise secured in an opening in the center of a bulged washer 23, which latter is secured around its edge to the 100 bottom of the can. The projecting end of the stub-axle 22 engages and is adapted to turn in a socket 24 fixed to the bottom of the ice-receptacle, the lower edge of the bulged washer 23 resting and turning against the 105 annular lip of said socket. A socket 25, square in cross-section, extends longitudinally through a portion of the length of

the stub-axle 22, opening at the upper end of the latter into the interior of the cream-can 17.

Within the cream-can there is located a beater or scraper-frame, which, as most clearly shown in Fig. 2, may be formed of flat strips of metal bent at their ends 26, 27, to overlap in a horizontal position, the vertical portions 28, 29, being bent to present 10 inclined blades with relation to the inner surface of the wall of the cream-can as the latter rotates in the direction indicated by the arrow in Fig. 4.

30 is a hollow shaft or spindle passing through and secured by solder or otherwise in vertical openings through the overlapping ends 26, 27 of the strips of the beater or scraper frame. The lower extremity of this tubular shaft or spindle fits over a bearing 20 on the bottom of the cream-can formed by the end of the stub-axle 22 projecting upwardly within the cream-can, while the upper end of said tubular spindle extends upward through the tubular flange 21 on the 25 cover 18, and has a squared extremity 40 over and about which the squared socket 15 of the cross-bar 8 is adapted to engage and prevent rotation of said tubular spindle and the beater and scraper frame attached thereto, and also serving to hold the cream-can and its associated parts in their vertical position during operation of the freezer.

31 and 32 are beater blades soldered or otherwise secured to the tubular spindle 30.

33 is a shaft or spindle extending vertically within the tubular spindle 30, and having its lower extremity squared or flattened at its sides to fit into the squared socket 25 of the stub-axle 22. At its upper 40 end shaft 33 is bent at right angles in a horizontal direction and carries a knob or handle 34, thus providing a crank which may be turned to rotate the cream-can, while the beater or scraper frame and blades 31, 32 attached to the tubular spindle 30, are held 45 against rotation by engagement of the socket 15 with the squared upper end 40 of said shaft 30.

In separating the parts the shaft 33 is 50 first withdrawn by pulling upward thereon. The free end of the cross-bar 8 is then disengaged from the rib around the upper edge of the ice-receptacle by an outward pull on the handle 12; cross-bar 8 is swung upward 55 disengaging socket 15 from the squared end 40 of tubular spindle 30. The cream-can and parts within may then be lifted out of the ice-receptacle and the cover 18 removed. The tubular shaft and parts fastened thereto 60 may then be lifted out of the cream-can, the lower end of said tubular shaft readily disengaging itself from the bearing formed by the inwardly projecting end of the stub-axle 22, which latter rotates in said lower end of 65 the tubular shaft when the freezer is being

operated. As will be apparent, this proceeding may be reversed in re-assembling the parts of the freezer.

With the parts assembled, as shown in Fig. 1, it will be apparent that rotation of the handle or knob 34, will cause the shaft 33 to rotate the cream-can by reason of the squared lower end of said shaft engaging the squared socket 25; during this operation the tubular shaft 30 and parts fixed thereto 70 will remain stationary by reason of the squared opening 15 of cross-bar 8 fitting about the squared upper end 40 of the tubular shaft.

What I claim is:—

1. In an ice-cream freezer, the combination of an ice receptacle; a cream-can having a bearing fixed to its bottom wall and mounted to rotate on an upright axis in the ice receptacle; a tubular spindle extending axially within the cream-can, the lower end of said spindle engaging and being held in position by said bearing, and the upper end of said spindle projecting through the top of the cream-can; means engaging said projecting end of the spindle to prevent it from rotating with the can; beating or scraping means carried by the spindle within the cream-can; a driving shaft adapted to be removably extended through the tubular 85 spindle and at its inner end connecting with the cream-can to rotate the latter; and means at the upper end of said driving shaft to rotate the same and with it the cream-can. 90

2. In an ice-cream freezer, the combination of an ice receptacle; a cream-can having a bearing fixed to and projecting upward from the bottom wall thereof, said cream-can being mounted to rotate on an upright axis in the ice-receptacle; a tubular 100 spindle extending axially within the cream-can, its lower end engaging about the upwardly projecting bearing to hold the spindle in position, and the spindle at its upper end projecting through the top of the 105 cream-can; means engaging said projecting end of the spindle to prevent it from rotating with the can; beating or scraping means carried by the spindle within the cream-can; a driving shaft removably extending through the tubular spindle and at its lower end engaging the upper end of the bearing within the spindle to rotate the cream-can; and means at the upper end of said driving shaft 110 to rotate the same.

3. In an ice-cream freezer, the combination of a cream-can, a tubular shaft carrying beating or scraping means axially mounted therein, and a cylindrical bearing carried by the bottom of the cream-can, said bearing extending upwardly within said can and journaled for rotation in the lower terminal of the tubular shaft. 115

4. In an ice cream freezer, the combination of a cream-can; a bearing carried by 120

the bottom of said can, said bearing being 5 cylindrical and extending upwardly within said can; a removable tubular shaft carrying beating or scraping means axially mounted in said can, the lower end of said shaft and said bearing being rotatably connected together; and a driving shaft adapted to be removably extended through said tubular shaft to engage said bearing.

10 5. In an ice-cream freezer, the combination of an ice receptacle, a cream-can rotatably mounted therein; beating or scraping means axially mounted in said cream-can, the lower end of said means being tubular; a bearing carried by the bottom of said cream-can, said bearing extending upwardly within said can and journaled for rotation in the tubular end of said means, and a driving shaft adapted to be removably extended 15 through said tubular end and at its inner end to engage said bearing to rotate the cream-can.

6. In an ice-cream freezer, the combination of an ice-receptacle, having a bearing 25 rising centrally from the bottom thereof; a cream-can; a tubular shaft axially mounted in said cream-can; a stub axle passing through the bottom of said cream-can and secured thereto, the portion beneath said 30 bottom engaging said bearing, and the portion above said bottom journaled for rotation in the lower terminal of said tubular shaft, and a driving shaft adapted to be removably extended through said tubular shaft and at its lower end to engage said 35 stub axle to rotate said cream-can.

7. In an ice-cream freezer, the combination of an ice-receptacle; a center bearing in the bottom thereof; a cream-can rotatably

mounted on said center bearing in said ice-receptacle; a tubular shaft carrying beating or scraping means axially mounted in said cream-can; means carried by the bottom of said cream-can to engage the lower end of said tubular shaft to prevent lateral displacement thereof; a cover for said cream-can, said cover having a flange to engage the upper part of said tubular shaft to prevent lateral displacement of said can; means for holding said tubular shaft stationary; and means for rotating said cream-can. 40 45 50

8. In an ice-cream freezer, the combination of an ice-receptacle having a bearing rising centrally from the bottom thereof; a cream-can; a tubular shaft carrying beating or scraping means axially mounted in said cream-can; a bearing carried by and passing through the bottom of said cream-can, the portion below said bottom engaging said bearing in the ice-receptacle and the portion 55 above said bottom journaled for rotation in the lower terminal of said tubular shaft; means for holding said tubular shaft stationary; a cover for said cream-can, said cover having a tubular neck to engage the upper part of said tubular shaft to prevent the lateral displacement of said cream-can and to engage said means to prevent the longitudinal displacement of said cream-can; and means for rotating said cream-can. 60 65 70

In testimony whereof I have signed this specification in the presence of two subscribing witnesses.
